UNITED STATES PATENT OFFICE

LEWIS FERRY MOODY, OF PHILADELPHIA, PENNSYLVANIA

REGULATING SYSTEM FOR HYDRAULIC TURBINES

Original application filed January 7, 1922, Serial No. 527,544. Divided and this application filed November 10, 1926. Serial No. 147,419.

This invention relates to a mechanism and system for controlling hydraulic turbine apparatus, and more particularly to the control of fluid flow to the turbine apparatus. This case is a division of my copending application filed January 7, 1922, Serial No. 527,544.

An object of the invention is to provide for a hydraulic turbine a regulating system having a plurality of regulating devices directly controlling the flow. Another object is to provide means whereby the devices are under a unified control for governing the speed and power of the turbine apparatus.

A more specific object of the present invention is to provide a single turbine unit with two types of regulating devices which in one specific aspect of the invention are gates, one being adapted for quick regulation to care for the usual load variations to which a plant is subjected, and the other being used for a slow adjustment. Other objects will be apparent from the following description of the accompanying drawing, in which

Fig. 1 is a partial vertical section through a turbine unit showing the governor and control mechanism in elevation, and

Fig. 2 is a sectional view of a valve mechanism.

In the illustrative embodiment of my invention I have shown a turbine runner R disposed within a plunger gate g, which comprises an inner member 5 slidable on an annular wall 6, while a piston 7 is disposed within an annular chamber 8. Fluid to the annular recess for moving the plunger gate upwards is conducted through a pipe 9 and controlled by an operating device, generally indicated h. The weight of the plunger and the water pressure exerted thereon will be sufficient for opening the plunger when fluid pressure in the chamber 8 is released. The upper end of the gate is curved to provide a smooth fluid passage leading to the turbine runner. The runner is supported

upon a usual shaft 10 which is connected to a usual generator T'. Fluid flow to the runner is also controlled by a series of wicket gates G', which are actuated by usual links 11 and a shifting ring 12, the shifting ring being actuated by a usual servo-motor 55. The wicket gates are disposed on the inside of stay vanes S disposed in the usual entrance passage E.

The turbine unit has an automatic speed governor 45 driven from the turbine and acting to control the wicket gates G' to vary relatively quickly the power supply according to the load, and to subsequently readjust the power supply at relatively slow rate. The governor 45, which is of the usual centrifugal flyball type or equivalent device performing the same functions, as for example an electrical device, is adapted through usual linkages to control the admission and exhaust of fluid to the servo-motor 55, thereby operating the wicket gates in the usual manner, while usual primary and secondary restoring mechanism including elements 52, 53 and 47 act upon the governor to prevent hunting and to restore the turbine to its normal speed.

It is desired in the arrangement herein disclosed to use in an individual turbine two different types of regulating means in the form of gates, one type of gate, the wicket gate, being employed for quick regulation to care for the usual load variations to which the plant is subjected, and the other type of gate, the plunger gate, being used for a slow adjustment under a secondary method of control. While gates have been specifically shown, it will be understood that there may be used other types of power regulating mechanisms by which power is variably obtained from the flow through the unit, such other types including adjustable runner vanes operated in any well known manner. By the arrangement described herein it will in general be unnecessary for the wicket gates to be capable of closing completely, or of

controlling the load throughout the entire power range of the unit; a small number of wicket gates could be used, widely spaced around the intake of the runner, thus reducing both the hydraulic friction of the gate surfaces and the hydraulic load which the operating mechanism must handle. For complete closure, or for handling large load changes, the plunger gate would be operated by the secondary control; for quick fluctuations, the wicket gates would operate under governor control. After any quick change in the position of the wicket gates corresponding to a change in load, the plunger would under the influence of the secondary control system slowly follow up the motion of the wicket gates until both the wicket gates and plunger gate have automatically adjusted themselves to corresponding degrees of opening.

The secondary control for the plunger gate is provided with a special operating stand *h* and connecting mechanism capable of moving the plunger gate at a slow rate compared to the wicket gate motion. To attain this operation, connections are provided between the wicket gate operating mechanism and the control stand *h*, and include a rod 50 which will partake of the movement of the gates *G'* through elements 52, and 53. The secondary control stand is shown on a larger scale in Fig. 2 and is connected to the rod 50 by a bell crank 56 and a vertical rod 57 running upward into the base of the control stand *h*. This rod 57 is connected to a horizontal floating lever 58. The left hand end of this floating lever is link-connected to the lever 60 linked to the plunger gate *g*. The center of the floating lever is connected to and actuates the stem 62 of a fluid pressure valve 63 contained in the upper portion of the control stand *h*.

The valve 63 is of the balanced piston type which when moved downward connects the pressure port 64 by pipe 9 to the lower end of the chamber 8 through port connection 66 to close the plunger gate. Upward movement of the valve 63 places port 66 and passage 67 in communication, thereby exhausting fluid in chamber 8 and moving the plunger gate to open position. The port 65 is used in certain installations for conducting fluid pressure to a second operating chamber but in this arrangement the gate is opened due to its weight and the water for the turbine acting thereon. The valve stem 62 passes through the valve and is screw threaded therein at 68 and swiveled at 69 and provided with a hand-wheel 70 so that the valve 63 may be moved either by vertical movement of the stem 62 or by rotational movement of the stem 62 when turned by the hand-wheel 70.

Assuming the gates of the turbine to be at rest at any given moment, a change in the

station load will cause the governor 45 to operate to move the gates *G'* and these in turn will move the horizontal interconnecting rod 50. The effect of this will be to raise or lower the right hand end of the floating lever 58, the left hand end of this lever being held stationary by its restoring rod connection 59 to the plunger gate. The middle of the lever 58 will move the valve stem 62 with a motion corresponding to that of the inter-connecting rod 50. This motion will open the hydraulic piston valve 63 admitting pressure to the chamber 8 and move the plunger in a closing direction. Shifting of the plunger gate will be communicated to the left hand end of the floating lever 58 and when the plunger gate has moved an amount corresponding to the motion of the interconnecting rod 50 the valve 63 will be restored to midposition. This gate motion will take place at a definitely restricted rate sufficiently slow so as not to interfere with the primary regulation of the unit. This restriction may be caused by a limited port area of the valve and a limited size of piping leading to the operating chamber of the plunger.

The action just described will cause the plunger gate to follow up the gate motion of the wicket gates and take up a corresponding position. While this automatic control by governor 45 is thus applied the hand control motion of hand-wheel 70 is always in gear, so that at any time an operator may superpose the hand control motion on all other controlled motions which are in progress. It is thus possible to shut down the unit by hand at any time, as in case of emergency, without first disconnecting any other mechanism, and it is also possible to adjust the valve 63 so as to proportion the positions of the wicket gates and plunger with relation to each other, in any desired manner.

The effect of the interconnecting mechanism is always to cause the plunger gate to follow up, and approach the position corresponding to that taken by the wicket gate.

The action just described is very effectively brought about in that the wicket gate is adjusted for quick operation while the plunger gate moves more slowly.

A further advantage of this plural arrangement of regulating means is that improved efficiency may be had by the joint action of both types of gates in that when they are both partially closed to the proper relative positions better operating conditions can be secured than by the use of either gate alone.

As a further means of controlling the unit an electric motor 72 may be provided contained within the base of the control stand *h* and connected through a worm 73 and worm wheel 74 and long faced pinion 75 to a gear 76 mounted on the vertical restoring rod 59 at the left end of the floating lever 58. This

gear 76 rotates a nut engaging a screw on the restoring rod so that by operating the motor the floating lever 58 may be raised or lowered and the valve 63 correspondingly moved. This motor 72 furnishes a remote control means by which the turbine may be operated from the switchboard or other convenient location. This remote control mechanism, therefore, like the hand control mechanism, is always in gear and it is not possible for an operator to leave it disconnected. The motor 72 may be arranged to operate directly on the valve spindle or stem 62 instead of upon the restoring rod 59, the effect being the same in either case.

My gate arrangement has the further advantage of being able to utilize the plunger gate to shut off positively fluid flow to the turbine runner when the turbine is idle, thus eliminating leakage; while during operation of the turbine, the plunger performs the additional function of regulating flow through the turbine and cooperates with the wicket gates to control the flow more efficiently.

Denoting the quick-acting flow controlling mechanism (here shown as wicket gates) the "primary gate mechanism", and the slow-acting mechanism (here shown as a plunger gate) the "secondary gate mechanism", then as explained above, the effect of the interconnecting mechanism is always to cause the secondary gate mechanism to follow up and approach the position corresponding to that taken by the primary gate mechanism under governor control due to a load change. After the first shift of the primary gates to take up practically the entire load change at a relatively rapid rate the effect will be for the primary gates gradually to unload a part of the load control upon the other gate mechanism, until only its proper share remains with the primary gate mechanism, that is, the secondary gate mechanism will gradually take up part of the control and relieve the primary gate until both gate mechanisms approach corresponding positions, leaving the unit with the adjustment of load then divided between both gate mechanisms. All quick fluctuations are taken by the primary gate mechanism and then the load adjustment is slowly distributed between the two gate mechanisms. If the load change is an increase in load, the primary gate mechanism will take the increase, its gates quickly opening so as to maintain as nearly as possible a constant speed of the unit. The secondary gate will then begin slowly to open and the primary gate will slowly close until both gates have reached an equilibrium as set by their respective governing valves.

I claim:

1. The combination with a hydraulic turbine having a runner and provision for directing fluid thereto simultaneously around its entire periphery, of a plurality of gate

mechanisms movable at different rates, each mechanism being movable relatively to the other and means for automatically effecting movement of one of said gate mechanisms upon movement of the other.

2. The combination with a hydraulic turbine having a runner and provision for directing fluid thereto simultaneously around its entire periphery, of a plurality of gate mechanisms, and means whereby one of the gate mechanisms is adapted to have an opening different from the other including means for coordinating the operation of said gate mechanisms.

3. The combination with a hydraulic turbine having a runner and provision for directing fluid thereto simultaneously around its entire periphery, of a plurality of sets of gate mechanisms, and means whereby operation of one set automatically effects operation of the other.

4. The combination with a hydraulic turbine having a runner and provision for directing fluid thereto simultaneously around its entire periphery, of a plurality of sets of gate mechanisms of different types, operating means for each, and means for coordinating the operation of said operating means.

5. The combination with a hydraulic turbine having a runner and provision for directing fluid thereto simultaneously around its entire periphery, of a gate mechanism for effecting a relatively quick fluid adjustment, and a second gate mechanism for effecting a relatively slow adjustment, and means for effecting said slow adjustment automatically after a quick adjustment.

6. The combination with a hydraulic turbine, of wicket and plunger gate mechanisms, and means whereby after movement of the wicket gate mechanism said plunger gate is moved automatically.

7. The combination with a hydraulic turbine, of wicket and plunger gate mechanisms, means for supporting said mechanisms in concentric relation, and means whereby after movement of the wicket gate mechanism said plunger gate is moved automatically.

8. The combination with a hydraulic turbine, of a plunger gate adjacent the turbine runner, a wicket gate surrounding said runner outside of the plunger gate, and means whereby after movement of the wicket gate mechanism said plunger gate is moved automatically.

9. The combination with a hydraulic turbine, of wicket and plunger gate mechanisms, means for rendering the operation of one of said mechanisms dependent upon the operation of the other, and means whereby said wicket gates are adapted to be only partially closed while said plunger gate is wholly closed.

10. The combination with a hydraulic turbine, of wicket and plunger gate mechanisms,

means for effecting relatively quick adjustment of said wicket gate mechanism, and means for thereafter effecting relatively slow adjustment of the other gate mechanism.

11. The combination with a hydraulic turbine having a runner and provision for directing fluid thereto simultaneously around its entire periphery, of a plurality of gate mechanisms, means for effecting relatively quick adjustment of one of said mechanisms, and means for effecting relatively slow adjustment of the second mechanism, including means whereby both of said mechanisms will approach automatically a substantially equal degree of opening in accordance with the turbine load.

12. The combination with a reaction type of hydraulic turbine having a runner and provision for directing fluid thereto simultaneously around its entire periphery, of a plurality of gate mechanisms, means for effecting adjustment of one of said mechanisms, including restoring mechanism, means for effecting adjustment of the other mechanism, and means for coordinating the operation of both of said means.

13. The combination with a hydraulic turbine having a runner and provision for directing fluid thereto simultaneously around its entire periphery, of a plurality of gate mechanisms, means for effecting adjustment of one of said mechanisms, including restoring mechanism, and means for effecting adjustment of the other mechanism, including another restoring mechanism.

14. The combination with a hydraulic turbine having a runner and provision for directing fluid thereto simultaneously around its entire periphery, of a plurality of gate mechanisms, means for effecting adjustment of one of said mechanisms including restoring mechanism, means for effecting adjustment of the other mechanism including another restoring mechanism, and means whereby one of said gate adjusting mechanisms is rendered operative after operation of the other adjusting mechanism.

15. The combination with a reaction type of hydraulic turbine having a runner and provision for directing fluid thereto simultaneously around its entire periphery, of means for controlling fluid flow thereto, including means for effecting quick control of the fluid, restoring mechanism for said quick control means, and means for effecting a slow control over the fluid flow automatically after the quick control has been effected.

16. The combination with a hydraulic turbine having a runner and provision for directing fluid thereto simultaneously around its entire periphery, of means for controlling fluid flow thereto, including means for effecting quick control of the fluid, restoring mechanism for said quick control means, and means for automatically thereafter effecting

a slow control over the fluid flow, including means whereby said adjustment is effected during a single change in the turbine load.

17. The combination with a reaction type of hydraulic turbine having a runner and provision for directing fluid thereto simultaneously around its entire periphery, of a plurality of gate mechanisms, means for effecting adjustment of one of said mechanisms, including a speed responsive governor having restoring mechanism associated therewith, and means for effecting adjustment of the other gate mechanism, including means controlled by said governor.

18. The combination with a hydraulic turbine having a plurality of gate mechanisms so relatively disposed that either of them is adapted when closed to prevent fluid flow to said turbine, of power operated means for effecting operation of each of said mechanisms and also relative adjustment therebetween, and hand controlled means for effecting adjustment of one of said mechanisms.

19. The combination with a hydraulic turbine having a plurality of gate mechanisms so relatively disposed that either of them is adapted when closed to prevent fluid flow to said turbine, of power operated means for effecting operation of each of said mechanisms and also relative adjustment therebetween, and hand controlled means for effecting adjustment of one of said mechanisms independently of the other mechanism.

20. The combination with a hydraulic turbine, of wicket and plunger gate mechanisms, a fluid actuated servo-motor for actuating said wicket gate mechanisms, fluid pressure operating means for said plunger gate, a speed responsive governor mechanism for controlling fluid flow to said servo-motor, a restoring mechanism associated with said governor for controlling said servo-motor, a valve for controlling actuating fluid for said plunger gate operating means, and restoring mechanism associated therewith, said latter valve being controlled by said governor.

21. The combination with a propeller type of hydraulic turbine having a runner and provision for directing fluid thereto simultaneously around its entire periphery, of a plurality of regulating means cooperating with the flow through said turbine to control the power and speed thereof, and means whereby operation of one of said plurality of means automatically effects operation of the other, said regulating means being adapted to have independent relative movement.

22. The combination with a hydraulic turbine having a runner and provision for directing fluid thereto simultaneously around its entire periphery, of a plurality of regulating means of different types cooperating with the flow through said turbine to control the power and speed thereof, and common con-

trol means for effecting operation of each of said regulating means.

23. The combination with a hydraulic turbine having a runner and provision for directing fluid thereto simultaneously around its entire periphery, of a plurality of regulating means of different types, cooperating with the flow through said turbine to control the power and speed thereof, one of said means having pivotally actuated elements, 10 a governor for controlling said pivot elements, and means connected to said pivot elements for movement therewith to control said other regulating means.

24. In combination with a hydraulic turbine having a propeller runner provided with unshrouded blades, of wicket gates and a cylindrical gate disposed on the outside of the turbine runner, both of said gates being spaced from said runner to provide a transition space, said wicket gates being adapted to impart variable degrees of whirl to the inflowing fluid to said turbine.

25. In combination with a hydraulic turbine having a runner, wicket gates adapted to impart varying degrees of whirl to the fluid flowing to said turbine, and stay vanes, of a cylindrical gate disposed outside of the runner and within the stay vanes.

26. In combination with a hydraulic turbine having an entrance casing, a runner disposed therein, and wicket gates and a governor, of means whereby said wicket gates are adapted for relatively quick actuation by said governor for regulating the speed and load of the unit, a cylindrical gate, and means controlled by said wicket gates for effecting relatively slow operation of said cylinder gate.

27. In combination with a hydraulic turbine having a runner and means forming an entrance passage thereto, of wicket gates for controlling said passage, and being adapted to impart varying degrees of whirl to inflowing fluid, and a cylindrical gate also being adapted to close said passage and so arranged that its closing movement is in a direction toward the turbine head.

28. The combination with a hydraulic turbine having a runner and provision for directing fluid thereto simultaneously around its entire periphery, of a plurality of regulating means cooperating with the flow through said turbine to control the power and speed thereof, means whereby said plurality of means are operatively connected but are mechanically independent whereby relative movement therebetween may be had.

29. The combination in a hydraulic turbine comprising a high specific speed propeller type runner, an entrance passage for turning the water from a radial to an axial direction, adjustable gates for controlling and variably whirling the flow therethrough and spaced from said runner to form a transi-

tion space, and a cylinder gate in addition to said adjustable gates.

30. The combination in a hydraulic turbine comprising a high specific speed propeller type runner, an entrance passage for turning the water from a radial to an axial direction, adjustable gates for variably whirling and controlling the flow therethrough and spaced from said runner to form a transition space, and a cylinder gate disposed on the inside of said adjustable gates.

31. The combination in a hydraulic turbine comprising a high specific speed propeller type runner, an entrance passage for turning the water from a radial to an axial direction, adjustable guide vanes disposed in the radial portion of said passage for controlling and variably whirling the flow therethrough and spaced from said runner to form a transition space, and a fluid-operated cylinder gate in addition to said adjustable vanes.

32. The combination in a hydraulic turbine comprising a high specific speed propeller type runner, an entrance passage leading thereto and having stay vanes therein, adjustable guide vanes also disposed in said entrance passage and being adapted to impart varying degrees of whirl to the inflowing fluid, and a cylinder gate adapted to close said passage and disposed on the inside of said stay vanes, said cylinder gate and guide vanes being spaced from said runner to provide a transition space therebetween.

33. The combination in a hydraulic turbine comprising a high specific speed propeller type runner, an entrance passage for conducting fluid thereto, fixed stay vanes in said passage, adjustable guide vanes also disposed therein and spaced from said runner to form a transition space and being adapted to impart varying degrees of whirl to the inflowing fluid, and a cylinder gate adapted to close said entrance passage and disposed on the inside of said stay vanes.

34. The combination in a hydraulic turbine comprising means forming a passage which turns from a radial to an axial direction, a runner disposed in said passage, adjustable wicket gates in the radial portion of said passage adapted to impart varying degrees of whirl to the fluid flowing to said runner, and a cylinder gate adapted to move axially of said runner and across the radial portion of said passage.

35. The combination in a hydraulic turbine comprising means forming a passage which turns from a radial to an axial direction, a runner disposed in said passage, adjustable wicket gates in the radial portion of said passage adapted to impart varying degrees of whirl to the fluid flowing to said runner, a cylinder gate adapted to move axially of said runner and across the radial portion of said passage, and stay vanes also disposed in the radial portion of said passage.

and adapted to maintain the opposed walls thereof in fixed spaced relation at all times.

36. The combination in a hydraulic turbine comprising means forming a passage which turns from a radial to an axial direction, a runner disposed in said passage, adjustable wicket gates in the radial portion of said passage adapted to impart varying degrees of whirl to the fluid flowing to said runner, a cylinder gate adapted to move axially of said runner and across the radial portion of said passage, and stay vanes also disposed in the radial portion of said passage and adapted to maintain the opposed walls thereof in fixed spaced relation at all times, said cylinder gate being adapted to move to its closing position against one of said walls.

37. In combination, an impeller, conduit means forming a vane-free space in advance of said impeller, means for varying the quantity of fluid passing through said space to said impeller, and adjustable means functioning independently of said quantity varying means for varying the direction of flow of said fluid relatively to said impeller.

38. In combination, an axial flow impeller, conduit means for directing fluid inwardly and axially toward said impeller, a gate for varying the quantity of fluid passing through said conduit means, and a series of adjustable guide vanes for varying the degree of whirl of the fluid admitted to said impeller through said conduit means.

39. In combination, an axial flow impeller, conduit means for admitting fluid axially toward said impeller, a gate movable axially of said impeller for controlling the quantity of fluid admitted through said conduit means, and adjustable means functioning independently of said gate for varying the degree of whirl of the fluid admitted to said impeller through said conduit means.

40. In combination, an impeller having a vane-free transition space in advance thereof, means for varying the quantity of fluid delivered to said impeller through said space, and adjustable means functioning independently of said quantity varying means for varying the degree of whirl of said fluid relatively to said impeller.

41. In combination, an impeller, conduit means forming a vane-free space in advance of said impeller, means for varying the quantity of fluid admitted to said impeller through said space, and adjustable means operable independently of said quantity varying means for varying the direction of flow of the fluid admitted to said impeller through said space.

42. In combination, an impeller, conduit means forming a vane-free transition space directly in advance of said impeller, means for varying the quantity of fluid admitted to said impeller through said space, and adjustable means located closely adjacent to said

quantity varying means for varying the direction of flow of fluid admitted to said impeller through said space, said direction varying means functioning independently of said quantity varying means.

43. In combination, an impeller, conduit means forming a vane-free transition space for conducting fluid along the axis of said impeller, means for varying the quantity of fluid flowing through said space, and adjustable means located in advance of said space and closely adjacent to said quantity varying means for varying the direction of flow of fluid admitted to said space, said direction varying means functioning independently of said quantity varying means.

44. In combination, an impeller having a vane-free space adjacent thereto, a gate movable axially of said impeller to vary the quantity of fluid passing through said space, and a series of adjustable guide vanes for varying the direction of flow of said fluid, said gate functioning independently of said guide vanes.

45. In combination, an impeller having a vane-free transition space directly in advance thereof, a gate movable axially of said impeller to vary the quantity of fluid admitted thereto through said space, and an annular series of adjustable guide vanes surrounding the axis of said impeller for varying the degree of whirl of the said fluid.

46. In combination, an impeller, means forming a passage comprising radial and axial flow portions connected by a transition space for conducting fluid to said impeller, means for relatively moving the bounding surfaces of said passage to control the quantity of fluid admitted to said impeller, and means functioning independently of said quantity controlling means for varying the degree of whirl of the entering fluid.

47. In combination, an impeller, conduit means for delivering fluid inwardly and axially toward said impeller, said conduit means comprising a movable wall forming a surface curving from the radial to the axial direction and said wall being movable to control the quantity of fluid delivered to said impeller, and means functioning independently of said quantity varying means for varying the degree of whirl of the fluid delivered to said impeller.

48. In combination, an impeller, conduit means for delivering fluid toward said impeller, said conduit means comprising a wall movable along the axis of said impeller to control the quantity of fluid admitted to said impeller, and means functioning independently of said quantity varying means for varying the degree of whirl of the fluid delivered to said impeller.

49. In combination, an impeller, conduit means for delivering fluid to said impeller, said conduit means comprising a wall mov-

able along the axis of said impeller to vary the quantity of fluid admitted to said impeller, and means movable about axes parallel to the axis of said impeller and functioning independently of said quantity varying means for varying the degree of whirl of the fluid delivered to said impeller.

5 50. In combination, an axial flow impeller, conduit means for delivering fluid axially with respect to said impeller, means movable 10 along the axis of said impeller to vary the quantity of fluid passing through said conduit means, and means movable about axes parallel to the axis of said impeller for independently varying the degree of whirl of 15 said fluid.
